UNITED STATES PATENT OFFICE

JAMES H. GRIFFIN, OF GRANTWOOD, NEW JERSEY

ROOF

Application filed November 7, 1927. Serial No. 231,713.

The present invention while applicable to water-tight floors or analogous structures is primarily adapted for incorporation in a roof, and the term "roof" will be used throughout the specification and claim, it being understood that the term is to be broadly interpreted.

An object of the invention is to provide a roof of slate or tile in which the necessity for overlapping the slate or tile is eliminated, a roof which will be entirely waterproof and weatherproof and otherwise efficient, and one which may be laid in a comparatively short space of time with about one-third of the quantity and weight of slate commonly used.

In a preferred embodiment of the invention the roof simply consists of a waterproofing covered with a trowel coating of quick setting mastic and a series of tiles or slates pressed into the mastic until the latter, partially or completely, fills the interspaces between them and lies approximately flush with the surface of the slate. In some instances where the mastic does not completely fill the interspaces a grout of Portland cement mixture may be used between the adjacent slates.

The invention is well suited for application to a new roof or for recovering an old roof. A light proof construction is provided which permits the use of slate on extremely low pitched roofs when slate shingles have heretofore been considered unsuitable due to the fact that rain beats in under them.

Special means may also be provided for anchoring the slate on an extremely steep roof so that the slate is securely held against slipping even in case of a fire softening the mastic.

With the above noted and other objects in view the invention consists in certain novel features of construction and combinations and arrangements of parts, which will be more fully hereinafter described and pointed out in the claim.

Figure 1 is a fragmentary side elevational view of an inclined roof with part of the waterproofing, mastic and slate laminations broken away to expose the material beneath them;

Figure 2 is a transverse sectional detail on the line 2-2 of Figure 1;

Figure 3 is a sectional view illustrating a modification and taken on the line 3-3 of Figure 5;

Figure 4 is a section showing the use of a cement grout between the interspaces of the slate; and

Figure 5 is a plan view of the modification shown in Figure 3.

As suggested above, the present construction and method may involve the use of either tile or slate. To avoid the use of alternate expressions in the specification and claim I shall simply use the word slate, intending to cover thereby tiles or equivalent materials.

In the drawings, I have used the reference numeral 10 to designate the boards of a roof. Laid directly upon the boards and secured thereto by cementing or in any other suitable manner is a layer of waterproof material 11 of felt, burlap or the like. Spread upon the burlap 11 is a trowel coating 12 of a quick setting mastic, such for instance as the mastic disclosed in my copending application, Serial No. 116,202, filed June 15, 1926. It will be recalled that this mixture consisted of asphalt and asbestos fiber and had a melting point of approximately 160° Fahr.

The slate 13 is then laid in the mastic, the slates being pressed in until the mastic is forced up into the interspaces between them, preferably filling such interspaces and lying flush with the outer faces of the slate. In instances where the interspaces are not completely filled they may be packed with a cement grout, as indicated at 14 in Figure 4.

It will be noted that the adjacent slates do not overlap but are laid in rows, with the slates of one row staggered relatively to the slates of an adjacent row.

A high melting point, quick setting mastic such as described above will be substantially set by the time the slate has been pressed into position, due to the cooling effect of the slate.

The weight of the slate is only about one-third of that employed ordinarily where the slate shingles are overlapped.

Where this method is used on a very steep roof I prefer to guard against accidental slip-

page of the slate in case the mastic becomes softened by the intense heat of a burning building. With this in view, I use securing devices consisting of wire rods 15 (Figures 3 and 5) which are embedded in the trowel coating of the mastic. These rods at one end are formed with pointed extensions 16, driven into the roof boards 10, and at their other ends with upstanding hook portions 17 disposed in the interspaces between adjacent slates and retaining the upper slate against downward movement. The rod 15 may either lie between two laterally adjacent slates or may be concealed under a slate.

15 Obviously various changes might be made both in the roof and in the method of laying it without departing from the spirit and scope of the appended claim.

I claim:

20 A roof, including a waterproof base, a mastic thereon, slates set in the mastic, the mastic substantially filling the interspaces between slates, and wire rods having pointed ends driven into the base, the intermediate portions of the rods being embedded in the mastic layer and the other ends of the rods being upturned to prevent sliding movement of the slates.

25 Signed at New York in the county of New York, and State of New York this 4th day of November, A. D. 1927.

JAMES H. GRIFFIN.
